UNITED STATES PATENT OFFICE.

ADRIAN H. AUSTIN, OF NEW YORK, N. Y.

DESIGN FOR ROSETTES.

Specification forming part of Design No. 7,628, dated August 11, 1874; application filed July 9, 1874.
[Term of Patent 3½ years]

To all whom it may concern:

Be it known that I, ADRIAN H. AUSTIN, of New York, in the county and State of New York, have invented certain new and useful Improvements in a Design for a Rosette; and I do hereby declare the following to be a full, clear, and exact description of the invention, such as will enable others skilled in the art to which it pertains to make and use it, reference being had to the accompanying drawings, which form part of this specification.

My invention relates to an improvement in designs for rosettes; and it consists in the configuration and form of the parts, which will be more fully described hereafter.

The accompanying drawing represents my invention.

a represents a leaf, of suitable shape or form, made of velvet or any other material that may be preferred. Upon the top of this leaf is placed the scalloped disk c, each scallop being convex on its upper side, and upon this is placed a button, e, of ornamental design.

Having thus described my invention, I claim—

The design for rosettes, substantially as shown and described.

In testimony that I claim the foregoing I have hereunto set my hand this 3d day of July, 1874.

ADRIAN H. AUSTIN.
